UNITED STATES PATENT OFFICE.

THEODORE MELDER, OF DEDHAM, MASSACHUSETTS.

BACKING-OFF ATTACHMENT FOR LATHES.

1,251,263.

Specification of Letters Patent. Patented Dec. 25, 1917.

Application filed January 4, 1917. Serial No. 140,485.

To all whom it may concern:

Be it known that I, THEODORE MELDER, a citizen of the United States, residing at Dedham, in the county of Norfolk and State 5 of Massachusetts, have invented new and useful Improvements in Backing-Off Attachments for Lathes, of which the following is a specification.

This invention relates to improvements in 10 backing off attachments for lathes or similar machines and has for its object to provide a simple and accurate device for reproducing teeth of various forms, as may be represented by a pattern, upon the work to form 15 milling cutters, hobs, and in fact practically all forms of rotary cutters.

Furthermore, the object is to provide means for detachably securing the pattern so that the same may be removed at will and 20 patterns of other designs or having different numbers and forms of teeth may be quickly and easily inserted.

The invention consists in the combination and arrangement of parts set forth in the 25 following specification and particularly pointed out in the claims.

Referring to the drawings:

Figure 1 is a plan view of a portion of a lathe, including both spindles thereof and 30 the tool support, together with the attachment embodying this invention, other portions of said lathe being eliminated to save space.

Fig. 2 is a side elevation of a finished cutter, illustrating one of the many forms which 35 may be produced by means of the device.

Fig. 3 is a detail side elevation of the attachment.

Fig. 4 is a section taken on the line 4—4 40 of Fig. 3.

Fig. 5 is a detail view of the connecting rod guiding member.

Fig. 6 is a detail sectional view of a pattern and its operating collar, illustrating 45 another method of detachably securing the pattern to the collar so that it may be quickly attached or detached in changing from one form of pattern to another.

Like numerals refer to like parts throughout the several views of the drawings.

In the drawings, 1 and 2 represent the 50 spindles of a lathe. 3 is an arbor pivotally mounted upon the spindles 1 and 2 and in the present instance operated by means of a dog 4 from the driving spindle of the lathe. This particular form of arbor and the man-

ner in which it is mounted is only shown for convenience, as many other forms may be employed in connection with the invention and the same will also be true of the 60 form of tool support used in the present case, and hereinafter described.

5 represents the work and is attached to the arbor 3 in the usual manner. 6 is the tool support or carrier of the lathe and is 65 preferably mounted to slide on a guide 7 toward and away from the arbor 3 while the guide 7 is carried by a slide 8 which is movable longitudinally of said arbor upon a suitable guide 9. A tool 10 is secured to the 70 tool carrier 6 in the usual manner, that is by a tool post 11.

The invention in its preferred form embodies a collar 12 mounted upon the arbor 3 and secured thereto preferably by means 75 of a screw 13. Detachably secured to the collar 12 is a pattern 14 consisting of a plate or disk having a series of teeth 15 disposed in its periphery. The number and contour of the teeth are substantially the same as the 80 number and contour of the teeth to be reproduced upon the work. This, of course, refers to the circumferential contour of said teeth but not the longitudinal contour thereof.

The pattern 14 is detachably secured to the collar 12 in the present form by means of screws 16. A follower 17 is arranged adjacent to the periphery of the pattern 14 and is constructed in the form of a pin arranged 90 parallel with the longitudinal axis of the arbor 3 and in contact with the teeth 15 of said pattern. The opposite ends of said pin project beyond the opposite faces of the pattern 14 and into recesses 18, 18 formed in a 95 pair of rings 19 and 20 arranged upon opposite sides of said pattern and preferably in contact therewith.

The ring 19 has a central opening 21 substantially larger in diameter than the collar 100 12 and in fact large enough to permit a movement of the ring 19 corresponding with the shape of the teeth of the pattern. The ring 20 also has a central opening 22 substantially the same size as the opening 21 105 and through this opening the arbor 3 and the heads of the screws 16 project.

Between the rings 19 and 20 is arranged a third ring 23 which has a central recess 24 within which the pattern 14 is arranged 110 to rotate, said ring substantially fitting the outside diameter of said pattern. A notch

25 is formed in said ring 23 to receive the follower 17 when said follower is in its outermost position with relation to the teeth of the pattern.

5 Operatively connected with the follower 17 is a connecting rod 26 which transmits the movement of said follower 17 to the tool slide 6. The means for connecting the rod to the follower 17 consists of a pin 27 disposed upon the opposite side of the arbor 3 from the follower 17. This pin projects into recesses 28, 28 formed in the rings 19 and 20.

To maintain the connecting rod 26 radial with respect to the axis of the arbor 3 a bearing 29 for said rod has been provided on the ring 23. The two rings 19 and 20 are secured together preferably by means of screws 30 which extend from the ring 20 through slots 31, 31 in the ring 23 and have screw threaded engagement with the ring 19. The slots 31 are long enough to permit the rings 19 and 20 to move eccentrically with the passing of each tooth of the pattern 14 by the follower 17 and during such movement the connecting rod 26 will be reciprocated in the guide or bearing 29.

Means have been provided for moving the follower 17 to the depth of each tooth 15 during the rotation of said pattern. This means preferably consists of a spring 32 arranged to encircle the rod 26 between the bearing 29 and collar 33 mounted upon said rod.

35 The end of the rod 26 is screw threaded at 34 and this end is adapted to be passed through a lug 35 formed upon a bracket 36 detachably secured to the tool slide 6 preferably by means of screws 37 and 38 so that said bracket may be adjustable longitudinally of said slide. The lug 35 has a slot 39 into which the end 34 of said rod is placed and permitted to be moved lengthwise of said lug in accordance with the adjustment of the slide 8 on the guide 9 of the lathe so that the tool 10 may be properly aligned with the work.

The collar 33 of said rod is adapted to seat against one face of said lug 35 while 50 a nut 40 is arranged upon the opposite side of said lug and has screw threaded engagement with said rod so as to impart movement to the tool slide through the bracket 36 and the lug 35 when the follower 17 is moved outwardly relatively to the axis of the arbor 3 by the teeth of the pattern. The end of the tool 10 is formed in accordance with the finished shape of the face of the work and the same is moved into contact 55 with the work 5 through the instrumentalities of the pattern 14 and the connecting means hereinbefore described.

In Fig. 6 I have illustrated a pattern member 41 attached to a collar 42 by means 60 of a key 43 instead of by screws 16, as illus-

trated in the previously described form. The key 43 projects into a slot in the member 41 and also into a slot 44 formed in a sleeve 45 which projects from the collar 42 through the hole in the pattern 41. The collar 42 is secured to the arbor 3 by means of a screw 46.

The operation of the attachment is as follows:

A pattern having the desired number of 75 teeth is attached to the collar 12 as shown, this being accomplished by removing the screws 30 and rings 20 and then in removing the screws 16 and pattern 14 and replacing the same with the pattern desired.

80 A blank constituting the work is placed upon the arbor as at 5, and the tool 10 having its end 47 formed to correspond with the finished face of the teeth to be cut upon said work, is adjusted properly with respect 85 to the face of said work and the lathe set into operation.

If the face of said work is extremely wide it will be necessary to first remove a very thin chip and before the work is entirely 90 completed a number of rotations of the arbor 3 will be necessary and at each rotation the tool may be advanced according to the thickness of the chip to be removed. Such an advancement of the tool may be accomplished either by rotating the usual slide operating screw or by rotating the nut 40 on the rod 34, thus advancing the slide 6, together with the tool 10. This method provides a fine, accurate adjustment for the tool. 100

The above description refers only to the application of this invention to an arbor which is rotated while the tool is held stationary, but in so far as the invention itself is concerned the arbor might be held stationary and the tool rotated and operated 105 equally as well.

Having thus specifically described my invention what I claim and desire by Letters Patent to secure is:

110 1. In a backing off device a pattern, a follower for said pattern, a rod connected with said follower, a guide member for said rod, a ring adapted to surround said pattern in contact with the periphery thereof and support said guide, and a spring adapted to maintain said follower in contact with said pattern.

115 2. In a backing off device a pattern, a follower for said pattern, a rod connected with said follower, a ring having rotatable engagement with said pattern, a guide member for said rod carried by said ring, and a spring adapted to maintain said follower in contact with said pattern.

120 3. The combination of an arbor, a collar secured to said arbor, a pattern detachably connected with said collar, a follower for said pattern, a rod connected with said follower adapted to be moved thereby radially 130

with respect to said pattern, a guide member for said rod having a portion arranged to encircle said pattern, and a spring encircling said rod and bearing against said guide member adapted to maintain said follower in contact with said pattern.

4. The combination of a pattern, a ring encircling said pattern and in contact with the periphery thereof, a follower for said pattern, a pair of rings mounted one upon each side of said follower and constituting supports for said follower, a tool carrier connecting rod connected with said carrier and with said rings, said rod having sliding engagement with said first named ring radially with respect to the axis of said pattern, means for rotating said pattern to impart movement to said tool carrier in one direction, and a spring adapted to maintain

said follower in contact with said pattern 20 and to move said tool carrier in the opposite direction.

5. The combination of a pattern, a follower for said pattern, supports for said follower arranged upon opposite sides of 25 said pattern, a tool carrier, a connecting rod interposed between said follower supports and said tool carrier, a guide for said connecting rod, and a spring surrounding said rod adapted to yieldingly retain said follower in contact with said pattern.

In testimony whereof I have hereunto set my hand in presence of two subscribing witnesses.

THEODORE MELDER.
